(57) **CLAIM**

I claim the ornamental design for a toy gun, as shown and described.

DESCRIPTION

FIG. 1 is a front perspective view of a toy gun according my design;

FIG. 2 is a bottom perspective view of the other side of FIG. 1;

FIG. 3 is a left side elevational view of FIG. 1;

FIG. 4 is a right side elevational view of FIG. 1;

FIG. 5 is front elevational view of FIG. 1;

FIG. 6 is a back elevational view of FIG. 1;

FIG. 7 is a top plan view of FIG. 1; and,

FIG. 8 is a bottom view of FIG. 1.

The broken lines shown represent portions of the toy gun that form no part of the claimed design.
